UNITED STATES PATENT OFFICE

CHARLES O. KARPF, OF BROOKLYN, NEW YORK, ASSIGNOR TO MANNINGTON MILLS, INC., OF SALEM, NEW JERSEY, A CORPORATION OF NEW JERSEY

PROCESS FOR DECORATING FLOOR COVERINGS

Application filed November 2, 1927. Serial No. 230,601.

My invention relates to processes for decorating floor coverings, particularly of the painted or printed surfaced variety.

During recent years there has been considerable development in the manufacture of inexpensive floor covering of the asphalt saturated felt base type, as substitutes for the more expensive inlaid linoleums. The serviceability of such floor covering is unquestioned and the purchase of the more expensive linoleums is primarily because of their superior appearance. It is the object of my invention to so decorate the wear surface of an asphalt felt base floor covering that the appearance of inlaid linoleum will be effectively simulated.

In printing floor covering I have found that if alternate squares in a checkerboard pattern are outlined in colors or shades of the main bodies of the adjacent squares that an appearance which resembles inlaid linoleum results. It is the object of my invention to decorate a printed rug accordingly.

The decorating of floor coverings may be done in a great many ways, and while I do not wish to be limited to the use of any particular manner of applying the colored or shaded coatings as the simplest method of printing a floor mat or rug, a base color coating of good floor paint is first applied. After this has dried the design is applied usually with mottled portions of the base coloring showing through giving the design a grained or mottled appearance.

I have illustrated in the drawings several different arrangements which will illustrate the principle of outlining certain squares or blocks so as to give the appearance of an inlaid pattern.

In the drawings:—

Figure 1 is a checkerboard design in which the mat is decorated with alternatively brown and green squares, with the green squares outlined with brown lines of a similar shade as that of the brown squares.

Figure 2 is the reverse of Figure 1 in which there are alternating green and brown squares, with the brown squares outlined with green lines of a shade similar to that of the green squares.

In the drawings the checkerboard designs are planned with equal sized squares. Thus, in Figure 1 the mat might be divided by imaginary lines such as are indicated by the lines *a*—*a*. This would divide the mat up into five green and four brown squares of equal size. A border of brown is then extended to form an outlining band of brown around each green square. The result is that the mat appears to the eye as having a brown background with green squares set into it, and the inlaid appearance is achieved.

In Figure 2 the mat might be divided by imaginary lines such as are indicated by the lines *b*—*b*. This would likewise divide the mat into equal squares. A border of green is then extended so as to form outlining bands of green around each brown square. The result in this case is that the mat has the appearance of a green background with brown squares inlaid into it.

In both cases the visual impression is undoubtedly aided by the extension of the border of one colored square as an outlining border for an adjacent square. This allows the eye to pass without a break from one square of one color diagonally to the adjacent square of the same color, and the squares which are not outlined thus appear to be inlaid.

Many modifications in the art of laying out the color or shade design for floor coverings will readily occur to those skilled in the art when the principle is once understood. A design of diamond shaped or circular blocks may be laid out in the same way with successive rows having a uniform appearance, and the alternating rows appearing to be set in the color ground of the uniform rows. It will further be possible to decorate each of the squares with a mottled color of two or more shades and outline the alternating squares with one or the other of the shades or colors used to make up the mottled design.

Having thus described my invention, what I claim as new and desire to secure by Letters Patent, is:—

1. The art of decorating printed floor covering with designs having the appearance of inlaid designs, which consists in arranging

rows of similarly shaped and similarly toned elements alternating in one direction across the covering and touching and blending one with another in another direction, and decorating the spaces intervening between the alternating rows with similar elements having different tones.

5 2. The art of decorating printed floor coverings with checkerboard designs, which will have the appearance of an inlaid pattern, which consists in arranging alternate rows of similarly toned squares in one direction across the covering, and in arranging contiguous squares of similar tone in directions at diagonals with the alignment of the alternate rows, and filling in the spaces not covered by the alternate rows with the shaded areas of different tone, said areas being completely outlined in a shade similar to that of the 10 first mentioned shaded squares.

15 3. The art of decorating printed floor coverings with designs simulating inlaid patterns, which consists in arranging a checkerboard design of alternating squares of contrasting tones, and outlining the alternating squares having a similar tone with a border of the tone of squares having a contrasting tone.

20 4. A printed floor covering comprising alternate contrasting elements arranged in a contiguous checker board design, one set of elements outlined in the tone of the other set whereby the said first set of elements appears to be inlaid.
